T. F. WARD,

INVENTOR.

BY
Geo. H. Kimmel, ATTORNEY.

UNITED STATES PATENT OFFICE.

THOMAS F. WARD, OF CLEVELAND, OHIO.

LOCK.

1,401,018.

Specification of Letters Patent. Patented Dec. 20, 1921.

Application filed May 27, 1921. Serial No. 472,960.

To all whom it may concern:

Be it known that I, THOMAS F. WARD, a citizen of the United States, residing at Cleveland, in the county of Cuyahoga and State of Ohio, have invented certain new and useful Improvements in Locks, of which the following is a specification.

This invention relates to improvements in locks and more particularly to that class of devices capable of use for a multiplicity of purposes and more particularly to sliding or swinging doors, and of such design as to constitute a spare tire lock or steering wheel lock for automobiles, and the like.

One of the objects of the invention resides in the construction of a lock of the type above set forth, wherein a pair of locking levers are adapted to be engaged by the end of a reciprocating rack bar movable by a key so as to release said levers from the keeper latch bar to unlock the same.

Another and very important object of the invention is the provision of a lock capable of universal use for various purposes and of such design that the parts will not readily get out of order being extremely simple in construction, easily assembled, rigid and durable, highly efficient in operation, practical yet capable of being manufactured at an extremely low cost whereby its commercial possibilities are greatly enhanced.

With these objects in view and others which will be manifest and suggested as the purpose and nature of my invention are revealed in the following specification and drawing wherein I have shown a preferred embodiment thereof.

Figure 1 is a front view of the lock casing, Fig. 2 is a view of the casing showing the top broken away,

Fig. 3 is a sectional view taken on the line 3—3 of Fig. 2,

Fig. 4 is a view showing the invention as applied to a sliding door,

Fig. 5 is a sectional view of the same,

Fig. 6 is a view showing the invention as applied and connected to the steering wheel of an automobile, and,

Fig. 7 is a view showing the invention as applied for locking a spare tire.

Referring now to the drawings, wherein like parts designate corresponding parts throughout the views, 5 designates a portion of a door and 6 the door jamb to which the lock is secured and operated in a manner now to be described in detail.

The lock proper consists of a front plate 7 which is partly cut away as shown at 8^a to be hingedly connected to the rear plate 8 by a pin 9 extending through bores formed in the respective plates 7 and 8 as clearly shown by Figs. 1, 2 and 3 of the drawing. The rear wall 10 of the lock is provided with a recess 11 near its outer end to permit a keeper 12 which is secured by suitable fastening elements 13 to the door jamb to extend within the body portion of the said lock to be engaged by the mechanism subsequently to be described. This plate 8 is also secured by suitable fastening elements 14 to the door proper and is normally retained in the countersunk portion 15 of the rear wall 10 of the casing.

The keeper 12 above referred to is in the nature of a cylindrical barrel 16, the top and bottom of which is open to receive the curved ends 17, 18, respectively, of a pair of locking levers 19 each of which are shown pivoted at 20 and held in locking position by the coiled springs 21 secured thereto and to an eye 22 attached to the rear wall of the casing.

The opposite ends 25 of the levers are shown cut at an angle to conform with the triangular end 27 of a lever operating rack 28, the triangular portion of the bar being provided with fingers 29 adapted to engage the ends 25 of the levers to rock the same on their pivots 20 and release the curved ends 18 from the keeper 16 above referred to. The opposite end 30 of the bar 28 is secured by a coiled spring 31 to one end of the casing, guide pins 32 being provided for the said bar 28 whereby the same will properly engage the cut away portions of the locking levers when actuated.

Referring to Fig. 2, it will be noted that the bar 28 is provided with teeth 33 formed on the top thereof for coöperation with a key operated barrel 34 provided with segmental teeth 35 which are in constant engagement with the teeth 33 of the bar, said barrel of course being rotatable to the left or right to its operative and inoperative positions by the usual key adapted to be inserted in the keyhole shown at 36.

By reason of this construction, it will be readily apparent that when the key is inserted in the keyhole 36 of the barrel 34 and turned to the right for instance, the bar 28 will be actuated so that the fingers 29 will engage the ends 25 of the locking levers and

release the opposite curved ends 17, 18 thereof from the keeper and thus the door may be opened. The pins 37 furthermore act in the nature of a stop for the triangular portion 5 of the bar 28 preventing the same from being withdrawn to a considerable degree by the coiled spring 31, the locking levers however being arranged to lie in proximity to the triangular portion 27 of said bar 28 to 10 be easily engaged thereby when the barrel 34 is rotated. It will be furthermore observed that the triangular portion 27 of the bar 28 and the pins 29 thereof are so arranged to coöperate with the cut away ends 15 25 of the levers that the bar 28 cannot be operated to force the triangular portion 27 thereof toward the ends of the locking levers to otherwise throw the lock out of order.

In the form of the invention shown by 20 Figs. 4 and 5, I have shown what may be a section of a garage door 40 provided with my novel and improved form of lock above described wherein an eye 41 is adapted to be rotated to actuate the flexible elements 42, 43 25 secured to a pair of top and bottom latches 44, 45 respectively, the bottom latch 45 in this instance, being operable by a connecting rod 47 whereby when the eye 41 is rotated the latch will be released from the floor to 30 permit the door to be opened. The connecting rod 47 extends through suitable eyes 48 which are in the nature of guides and are attached to a spring latch 49 which retains the upper end of a door stop 50, hingedly 35 connected at 51 to the latch 45 so that when the member 49 is raised to the dotted line position 50 the hinged door stop will fall to its dotted line position as shown by Fig. 5 to retain the door open.

40 In Fig. 6, I have shown my invention as applied to a steering post 53 and steering wheel 54 wherein the lock 55 may be secured to one of the wheel spokes 56 and hingedly connected at 57 by means of any suitable 45 clamping device 58 whereby the said wheel 54 may be held in locking position and thus prevent unauthorized operation of the motor vehicle.

Similarly in Fig. 7, I have shown my invention as applied as a locking means for a 50 spare tire 60, shown in dotted lines, in which the lock 61 is suitably secured to the respective sections 62, 63 of a clamping member, hingedly connected as at 64 whereby the tire 55 may be removed when so desired by unlocking the said clamp.

In the accompanying drawings, I have 60 illustrated my invention embodied in one form by way of example, and which in practice has been found to be highly satisfactory in obtaining the desired results. It will be obvious however that other embodiments 65 may be adopted and that various changes in the details of construction may be resorted to by those skilled in the art without de-

parting from the spirit and scope of the invention. It is furthermore understood that the invention is not necessarily limited or restricted to the precise elements shown except in so far as such limitations are specified in the subject matter being claimed. 70

Having shown and described my invention, what I now claim as new and desire to secure by Letters Patent of the U. S. is:—

1. A lock of the class described in combination with a keeper, comprising a casing, curved locking levers pivoted within said casing, each of said levers having one end coöperatively engaged by said keeper, a rack bar for engaging the opposite ends of the 75 levers to release the same from locking engagement, and means for reciprocating said bar.

2. A lock of the class described in combination with a keeper, comprising a casing, 80 curved locking levers pivotally secured to the inner rear wall of the casing, each of said levers having one end adapted for locking engagement with the keeper, a reciprocable rack bar for engaging the opposite 90 ends of the levers to release the same from locking engagement and rotatable means for actuating said rack bar.

3. A lock of the class described in combination with a keeper, comprising a casing, 95 curved locking levers pivotally secured to the inner rear wall of the casing, each of said levers having one end adapted for locking engagement with the keeper, coiled springs for normally maintaining said ends 100 in locking engagement, a reciprocating rack bar coöperating with the opposite ends of the levers to release the same, guides for said rack bar, one of said guides constituting a stop for the rack bar, rotatable means 105 for urging the said bar into engagement with the ends of said levers to unlock the same.

4. A lock of the class described in combination with a keeper, comprising a casing, 110 curved locking levers pivotally secured to the inner wall of the casing, each of said levers having its curved end adapted for locking engagement with the said keeper, coiled springs secured to each of said levers 115 and to the casing for maintaining said curved ends in locking engagement, a horizontal, reciprocating rack bar coöperating with the opposite ends of the levers, a coiled spring secured to one end of the rack bar 120 and to the casing whereby the said bar is held out of engagement with the levers, guides for said bar, and key operated means for urging the opposite end of said bar into engagement with the levers to unlock the 125 same from the keeper.

5. A lock of the class described in combination with a keeper, comprising a casing, curved locking levers pivotally secured to the inner rear wall of the casing, each of 130

said levers having its curved end adapted for locking engagement with said keeper, coiled springs secured to each of said levers and to the casing for maintaining said 5 curved ends in locking engagement, a horizontal reciprocating rack bar, a triangular enlargement and figures carried thereby formed at one end of the rack bar coöperating with the opposite ends of the levers, a 10 coiled spring secured to the opposite end of the rack bar and to the casing whereby the

bar is held out of engagement with the levers, guides for said bar constituting a stop for the triangular enlargement when the bar is in its normal position, and rotatable means 15 having teeth thereon coöperating with the rack bar for urging the same into engagement with the levers.

In testimony whereof I affix my signature hereto.

THOMAS F. WARD.
